UNITED STATES PATENT OFFICE.

ABRAHAM NOVICK, OF NEW YORK, N. Y., ASSIGNOR TO UNITED STATES ENVELOPE COMPANY, OF SPRINGFIELD, MASSACHUSETTS, A CORPORATION OF MAINE.

ENVELOP-MACHINE.

1,291,089.

Specification of Letters Patent. Patented Jan. 14, 1919.

Continuation of application Serial No. 795,629, filed October 17, 1913. This application filed October 15, 1917. Serial No. 196,754.

To all whom it may concern:

Be it known that I, ABRAHAM NOVICK, a citizen of the United States, residing at New York, in the county of Kings and State of New York, have invented certain new and useful Improvements in Envelop-Machines, of which the following, together with the accompanying drawings, is a specification, the present application being a continuation 10 of my pending application, Serial No. 795,629, filed October 17, 1913.

The present invention relates to envelop machines, and more particularly to such machines of the so-called rotary type wherein 15 the various operations in the manufacture of envelopes, including the forming of blanks, and the gumming and folding of said blanks, are performed in a continuous manner by the passage of the material from end to end in 20 the machine, in rolling contact with the various instrumentalities thereof.

More particularly, the machine of the present invention contemplates, initially, the production of blanks substantially parallelogrammic in form from a continuously moving web of material, the blanks being cut on the bias, or diagonally, from said web, in order to economize stock and reduce the waste to a minimum. The blanks thus continuously severed are thereafter successively subjected to the action of novel and improved gumming and folding devices, as hereinafter described, for forming them into completed envelopes, and in order to present said blanks 30 in symmetrical disposition with respect to said gumming and folding devices, the machine of the present invention includes suitable mechanism for changing the direction of the blanks in transit from the original 35 direction of the web,—this being necessitated by the diagonal position of each blank which is severed from the web.

The above and other objects are attained by the combination and arrangement of 45 blank forming, gumming and folding instrumentalities hereinafter described in detail, reference being had in this connection to the accompanying drawings, in which—

Figure 1 is a plan view of a machine embodying the invention.

Fig. 2 is a longitudinal side view of said machine, as seen from the front side thereof.

Fig. 3 is a vertical sectional view of a portion of the mechanism shown in Fig. 2.

Fig. 4 is a detached view of a cutting cylinder used in the formation of blanks from the web of material. 55

Fig. 5 is a detached view of another cutting cylinder, for severing the blanks from the web. 60

Fig. 6 is a sectional view of the cylinder shown in Fig. 5.

Fig. 7 is an elevation of the machine, as viewed from a position at right angles to the position of Fig. 2. 65

Fig. 8 is a vertical sectional view of a portion of the mechanism appearing in Fig. 7.

Fig. 9 is a detached detail view of mechanism at the left hand end of Fig. 8.

Fig. 10 is a plan view of the side flap 70 folding mechanism in a different position from that illustrated in Fig. 1.

Fig. 11 is a transverse sectional view of the mechanism shown in Fig. 10.

Figs. 12 and 13 are detached detail views 75 illustrating different positions of operation of the seal flap folding mechanism which is shown in Fig. 8.

Fig. 14 is a similar view illustrating a modification of said seal flap folding mechanism. 80

Fig. 15 is a diagrammatic view illustrating the successive steps in the manufacture of completed envelopes from a continuous web of material, according to the present invention. 85

Like reference characters refer to like parts in the different figures.

The operative parts of my improved mechanism are represented in the present instance as mounted on a suitable table 1, which has supporting legs 2, 2. The table 1 supports a pair of longitudinal side frames 3 and 4, and substantially at right angles to the latter a pair of transverse side frames 95 5 and 6. Power is imparted to the mechanism from a suitable source, not shown, by means of a belt pulley 7 on main driving shaft 8, the latter being suitably journaled in the side frame 3. The shaft 8 carries a pinion 9 which is in mesh with a gear 10 on a countershaft 11, also journaled in the side frame 3. Above the shaft 11 is journaled a shaft 12, which is driven from the shaft 11 by means of intermeshing gears 13 and 14. 100 The gear 14 on shaft 12 serves to actuate the web advancing and blank cutting devices of my mechanism, as hereinafter described. 105

The continuous web, as indicated at A, Figs. 1, 2 and 3, is taken from a roll A' Fig. 2, and is continuously forwarded between the bight of feed rolls 15 and 16 which are carried on shafts 17 and 18 respectively having suitable bearings in the frames 3 and 4. Said shafts carry intermeshing gears 19 and 20, the first named gear being also in mesh with the gear 14 on shaft 12, whereby the feed rolls 15 and 16 are rotated in unison, continuously, to move the web A forward. In advance of said feed rolls are provided cutting cylinders 21 and 22, which are carried on shafts 23 and 24 respectively having suitable bearings in the side frames 3 and 4. Said shafts carry intermeshing gears 25 and 26, the first named gear being in mesh with the gear 14 on shaft 12, whereby the cutting cylinders 21 and 22 are driven in the same direction, relatively, as the forward rolls 15 and 16.

The cutting cylinder 22, in the present instance, is constructed as represented in Fig. 4. Said cylinder carries at each end thereof a pair of cutters 27, 27, for making the notches 28 in the edge of the traveling web A, as shown in Fig. 15. Said cylinder 22 also carries a centrally disposed cutter 29, for making at each revolution a center cut 30 in the web, as shown in Fig. 15. The cutters 27 and 29 of cylinder 22 coöperate with the surface of cylinder 21 in making the four edge cuts 28 and the single center cut 30 in the web at each revolution, the surface of cylinder 21 being preferably hardened for this purpose. The pieces or chips of the web A which are defined by these cutting operations may not become entirely separated from the web on account of the fact that some of the fibers of the material remain unsevered, and it may be necessary to employ a mechanism for removing these partially separated chips from the traveling web. Such a chip removing mechanism may take any suitable form, such as that shown in my copending application Serial No. 798,236, filed October 30, 1913. The details of such mechanism constitute no part of the present invention, and hence a description or showing thereof is unnecessary.

In advance of the cylinders 21 and 22, the machine herein shown provides cutting cylinders 40 and 41, which are carried on shafts 42 and 43 respectively, having intermeshing gears 44 and 45. The latter of said gears is in mesh with an intermediate gear 46 that is driven from the gear 25 of the cylinder 21. One of said cutting cylinders, here shown as the cylinder 41, Figs. 5 and 6, provides a substantially helical cutting blade 47, which is secured thereto in any suitable manner, as by means of a retaining screw 48 entering recess 49 in the periphery of said cylinder. Said blade 47 coöperates with the surface of opposite cutting cylinder 40 to

sever the traveling web A on successive oblique lines 50, Fig. 15, whereby to form blanks which are substantially parallelogrammic in outline. The cutting cylinders 40 and 41 are rotated in the same relative directions as the cutting cylinders 21 and 22, by the gearing as above described, and the speeds of all said cutting devices are so timed that the lines of cut 50 will intersect the opposite corners of center cut 30 as well as the apexes of those notches 28 which are directly in line with each center cut 30, as clearly shown in Fig. 13. Instead of separate pairs of cutting cylinders 21, 22 and 40, 41 respectively, the functions above described may obviously be performed by a single pair of cylinders, the cutter carrying member of which would have the blade 47 in addition to the cutters 27 and 29.

In advance of the cutting devices as heretofore described, the machine of the present invention provides cylinders 52 and 53 for forwarding the separated blanks in the line of travel of web A, each blank being received into the bight of said rolls 52 and 53 in an oblique position. That is, the oblique line 50 constitutes the advancing edge of successive blanks in each instance, said edge being formed by contiguous portions of one of the longitudinal flaps and one of the side flaps of the blank, as shown clearly in Fig. 15. With the blanks traveling in this direction, with such an oblique edge foremost, there is no way in which the same may be centered and squared for the subsequent gumming and folding operations of the machine, and the present machine contemplates such a change in the direction of movement of the blanks as will permit of their advancement in a symmetrical relation to the machine as regards their projecting side, back and seal flaps, and at the same time retaining the advantages incident to cutting and forming the blanks in the manner above described, with a minimum waste of stock.

To this end the cylinders 52 and 53 are rotated so as to advance the separated blanks continuously through the machine, said cylinders being carried on shafts 54 and 55 respectively which have intermeshing gears 56 and 57. The former of said gears is in mesh with an intermediate gear 58 that is driven from the gear 44 of cutting cylinder 40, whereby the cylinders 52 and 53 are rotated in unison, in the same direction relatively as the previously described forwarding, cutting and chip removing cylinders to move the blanks in substantially the same direction as the web A. The requisite change in direction, or partial rotation of the separated blanks, is effected by devices in advance of the cylinders 52 and 53, as hereinafter described, and for the purpose of releasing each blank, just prior to the commencement of this movement, one of said

cylinders, in the present instance the cylinder 53, has a segmental cutaway portion 59. This portion 59 enables the blank to be drawn out of the bight of rolls 52 and 53 by the direction changing devices, when the advancing edge of said blank is seized thereby, as hereinafter described. It is to be understood, however, that my invention is not confined to the particular means herein shown and described for releasing the blank from the bight of forwarding rolls 52 and 53, namely the segmental cutaway portion 59—it being clear that any equivalent releasing means, such as a mechanism for momentarily separating said rolls at the proper period in their revolution, could as well be employed.

The direction changing devices for operation on the separated blanks consist in the present instance of coacting frusto-conical rolls 60, 61, arranged with converging axes at an angle oblique to the parallel axes of the previously described blank advancing cylinders 52 and 53. Said rolls 60 and 61 are carried on shafts 62 and 63 respectively, which are journaled in suitable brackets 64 and 65 supported on table 1. The shafts 62 and 63 carry intermeshing gears 66 and 67, which are slightly beveled to compensate for the convergence of said shafts. The shaft 62 of lower roll 60 carries a bevel gear 68 which is in mesh with a bevel gear 69 on a transverse shaft 70, the latter being driven by bevel pinions 71 and 72 from a shaft 73. The latter is rotated in synchronism with the blank cutting and advancing devices of the machine by a bevel gear connection 74, 75 with the main driving shaft 8.

The separated blanks as received in the bight of conical rolls 60, 61 have their direction of advancement varied, by reason of the greater peripheral speed of the larger ends of said rolls, as will be understood. The blanks are swung gradually through the path indicated by the broken lines B, B, Fig. 15, their motion of translation being continued during their rotation, so that they finally assume the position indicated at C, Fig. 15, in which the projecting side and longitudinal flaps are symmetrically disposed about the rectangular portion which defines the shape of the completed envelop or inclosure. In this position their advance is adapted to be continued, in a straight line, by means of coacting cylinders 76 and 77, Fig. 8, which are journaled in the side frames 5 and 6 with their axes at right angles to the axes of cylinders 52 and 53. The cylinders 76 and 77 are substantially the counterparts of cylinders 52 and 53, in that one of the former, in the present instance cylinder 77, has a segmental cutaway portion 78, which prevents said cylinders from seizing the advancing edge of the blank until the turning movement of the latter to

bring it into the position C has been completed. Obviously, any equivalent means for accomplishing this same result could be employed. The cylinders 76 and 77 coöperate in advancing the blank to the blank 70 centering, squaring, gumming and folding devices of the machine, as hereinafter described. Said cylinders 76 and 77 are rotated by suitable intermeshing gears 79 and 80, one of which, 79, is shown in Fig. 7 as 75 being driven from a gear 81 on shaft 82, the latter having a bevel gear connection 83 with shaft 70.

For facilitating the blank turning action of the conical rolls 60, 61, I provide coacting pairs of short cylindrical rolls 84, 85 and 86, 87 which are located respectively on opposite sides of said conical rolls, between the same and the adjacent pairs of cylinders 52, 53 and 76, 77 respectively. Said rolls 84, 85 and 86, 87 are carried on shafts 88 and 89 respectively, having intermeshing gears 90 and 91. The former of said gears is driven by an intermediate gear 92 which is in mesh with gear 56 of cylinder 52, whereby the rolls 84 and 85 are rotated continuously in the same relative directions as cylinders 52 and 53. Said rolls 84, 85 are considerably shorter than the cylinders 52, 53, whereby they may be placed in close proximity to the conical rolls 60, 61, in order to insure the feeding of the edge of each separated blank to the bight of said conical rolls near the outer larger ends of the latter. One of the rolls 84, 85, in the present instance the upper roll 85, has a segmental cutaway portion 93 similar to the portion 59 of cylinder 53, whereby the release of a blank is effected when the latter is seized by the conical rolls 60, 61. The rolls 86, 87 are substantially counterparts of the rolls 84, 85, one of them, in the present instance the roll 87, having a segmental cutaway portion 94 which prevents said rolls from seizing the blank until the latter has been released by the conical rolls 60 and 61. Said rolls 86, 87 are driven by intermeshing gears 95, 96 respectively, Fig. 7, one of which is in mesh with an idler 96 that is driven from gear 79 of roll 76.

One of the conical rolls, in the present instance roll 61, has a segmental cutaway portion 97, which becomes operative to release the blank from the bight of said rolls at the end of their turning operation thereon, just before said blank is seized in the bight of rolls 86, 87. In the operation of the above described mechanism, the separated blanks are each in turn moved continuously into the conical rolls 60, 61, and the final rolls 84, 85 operate to swing the outer end or edge of the blank while remaining inoperative with respect to its inner end or edge. The latter partakes of the gradual movement of translation which is accomplished by the smaller inner ends of conical rolls 60, 61, and is not

operated upon by the rolls 86, 87 which act only on the more rapidly moving outer end or edge. The segmental cutaway portion 93 releases the blank from the bight of rolls 5 84, 85 just as the blank is seized in the bight of conical rolls 60, 61, and the segmental cutaway portion 97 releases the blank from said conical rolls just as said blank is seized by rolls 86, 87. The latter complete the wide 10 swinging movement of the outer end or edge of the blank, and therafter the forward edge is seized in the bight of rolls 76, 77 and the blank is advanced into the position C for the operations of centering, squaring, gumming 15 and folding, as hereinafter described.

It will be seen that the successive blanks, as cut obliquely from the web A, have their speed of advancement in the direction of said web gradually reduced as they come 20 into the bight of conical rolls 60, 61. Simultaneous with their reduction in speed in the direction of web A, there is a combined movement of translation and rotation by said conical rolls and by the short rolls 25 84, 85 and 86, 87 which carries the blanks through a curved path, whereby they come into symmetrical relation to the direction of advance of the forwarding rolls 76, 77.

As the blanks are successively turned into 30 the position C, wherein they are symmetrically disposed for the further operations of gumming and folding thereon, they are adapted to receive, if desired, a spot of gum on the under surface of one of the side flaps, 35 as indicated at 98, Fig. 15. In the present construction the roll 86 is adapted to perform this function, said roll being made shorter than its coacting roll 87, as shown in Fig. 9, and carrying on its shaft a gumming 40 arm 99, of the proper size and in the required relative position for making contact with the tip of the side flap of each blank passing thereabove. The arm 99 makes contact at another part of its revolution with 45 the periphery of a gum transfer roll 100, which is revolvably mounted and partially submerged in a gum box 101, being driven from the shaft of idle gear 96'. The above described gumming operation is useful in 50 insuring the adhesion of the two side or end flaps of the blank, when the latter are folded over into contact, as shown at 102, Fig. 15, but obviously said operation may be entirely omitted without detracting in the 55 least from the efficiency of my machine.

In advance of the rolls 76 and 77, the frames 5 and 6 support a pair of shafts 103 and 104, having intermeshing gears 105 and 106 respectively, the former of which is driven from the gear 81, Fig. 7. The shaft 60 103 provides a cylinder 107, around which pass a plurality of endless conveying belts 108, which encircle at their other end a cylinder 109 on shaft 110. The upper courses 65 of these belts serve as conveying means for

the successively received blanks, and the belts are operated at a speed which accelerates the movement of the blanks over the speed imparted thereto by the rolls 76 and 77. The shaft 104 carries a plurality of segmental disks 111 which coöperate with the belts 108 in effecting the delivery of the blanks onto said belts, and a shaft 112 at the other end of said belts carries disks 113 which effect the delivery of the blanks from 75 said belts. Said shaft 112 carries a gear 114 which is in mesh with a gear 115 on the belt driving shaft 110, and said gear 114 is driven from an idler gear 116, the latter being in mesh with a gear 117 on shaft 118. The 80 gear 117 is driven from gear 81 by means of an idler 119.

While on the belts 108, each blank is adapted to have its side flaps folded inwardly, and on account of the necessity for 85 bringing each blank to a momentary rest for this purpose, the belts are timed to increase the speed of each blank, as heretofore described. The blanks are held in firm frictional engagement with the upper courses 90 of belts 108 by means of gravity resting balls 120, Fig. 8, which are loosely carried in rearwardly projecting portions of a cross member 121, supported by the frames 5 and 6 above the plane of advance of the 95 blanks. At its rear portion said member 121 carries guides 122, which prevent the displacement of the blanks from the belts 108. At its forward portion, the member 121 supports a stationary forming plate 100 123, which is spaced slightly above the upper courses of belts 108 to permit the blanks to enter edgewise between said forming plate and said belts.

A pair of fixed registering pins 124, 124 105 are suitably mounted on inwardly extending brackets 125, so as to project in the path of the flat blanks at the forward corners of forming plate 123, Fig. 1. These registering pins are adapted to interrupt the movement of a blank by the belts 108, and at the same time to coöperate with the advancing edge of said blank to center and square the same preliminary to the side flap folding operation, by their engagement with the re- 110 entrant angles 28, 30 of said edge. In other words, if a blank on the belts 108 is out of alignment, the pin 124 first engaged by its leading edge will act as a pivot until the blank is brought up square with the other pin, due to the constant frictional contact of the blank with the traveling belts 108. This movement of belts 108 will also cause the advancing edge of the blank to slide along the pins 124 until said pins reach the 125 reentrant angles 28, 30, thus bringing the blank into registered position beneath the forming plate 123.

The lateral edges of said forming plate lie inwardly slightly of the pins 124 and said 130

edges constitute the folding edges for the projecting side flaps of the blank. After the centering and squaring of the blank as above described, said projecting side flaps which are disposed in the positions indicated at 126, 126, Figs. 1 and 11, are acted upon by reciprocating folder plates 127, 127, which are carried on supporting members 128, 128 having suitable guideways 129, 129 5 in the brackets 125. The lower ends of said supporting members are received in oppositely disposed curved grooves 130 in a pair of cylinders 131 carried by rotating shaft 118, and adapted simultaneously to draw 10 the folding plates 127 together, and thereby force the side flaps 126 upwardly and inwardly over the lateral edges of forming plate 123, as shown in Figs. 11 and 15. Thereafter, upon the simultaneous retraction 15 of folding plates 127, the blank is free to be moved forwardly by the belts 108 since the advancing edge of said blank is entirely between the pins 124.

As herein shown the belts 108 and disks 25 113 deliver the blanks, with their side flaps thus folded, to the bight of printing cylinders 132, 133, of which the former may be a type cylinder and the latter an impression cylinder. Said cylinders 132 and 133 are 30 carried on shafts 134 and 135 respectively, having intermeshing gears 136 and 137, the former being driven by an idler 138 from the gear 115 of shaft 110. Ink may be supplied to cylinder 132 through the usual rolls 35 139 and 140, spreader 141, and the usual transfer vibrating ductor and fountain devices indicated as a whole by the numeral 142, Fig. 7. It will be understood that the use of the above described or any other 40 printing mechanism, for impressing an address or the like on the under surface of the blank is entirely optional and, if desired, such mechanism may be dispensed with, and the blanks delivered instead directly to the 45 seal and back flap gumming and creasing mechanisms, which will now be described.

Feed rolls 143 and 144 are adapted to seize the blanks as they leave the belts 108 or the printing mechanism, as the case may be, and 50 advance the same successively for further operations thereon. Said feed rolls are carried on shafts 145 and 146 respectively having intermeshing gears 147 and 148, the latter being driven through an idler 149 from the gear 137 of the printing mechanism. In 55 advance of said feed rolls are disposed shafts 150 and 151 having intermeshing gears 152 and 153, the former of which is driven through an idler 154 from the gear 147 of feed roll shaft 145. The shaft 151 carries a segmental gumming member 155, which supports a back flap creasing blade 156 and a seal flap creasing blade 157. These blades coöperate, in the order named, 60 with grooves 158 and 159 respectively in the surface of a roll 160 on shaft 150, to crease the blank as it passes between member 155 and roll 160, on the lines 161 and 162 respectively, Fig. 15. By the coöperative action of blade 156 with groove 158, the advancing or back flap of the blank is deflected upwardly, as shown at 163, Fig. 8, and the same is true of the rear or seal flap of the blank when the blade 157 and groove 159 become operative with respect thereto. 70

The member 155, in addition to the creasing functions above described, is operative as a gumming device, to apply the strips of gum 164, 164, Fig. 15, to the side flaps in readiness for the folding over thereon of the 80 creased seal flap 163. To this end the surface of member 155, between the blades 156 and 157, is adapted to receive a suitably disposed line of gum alternately from gumming ledges 165, 165, which are carried by 85 rotating arms 166, 166. Said arms are mounted on a shaft 167 which has a gear 168 in mesh with the gear 153 of shaft 151. The gumming ledges 165 are adapted to make contact in their rotation with a gum roll 90 169 which rotates in a suitable gum box 170. The arms 166 also carry suitably shaped gumming ledges 171, 171, supplied from the roll 169 and adapted alternately to lay a line of gum on the surface of member 155 behind the blade 157, whereby to gum the seal flap, as shown at 172, Fig. 15.

In advance of the gumming and creasing devices above described, the blank is projected onto a supporting guide 173 which is 100 carried on a transverse stationary rod 174. A stationary guiding rod 175 is so spaced above the guide 173 as to engage the upwardly deflected back flap 163 of the blank, and by the continued advancement of said 105 blank to fold or turn said flap into the position indicated by the broken line 163', Fig. 8. Thereafter said back flap is completely folded down, and pressed into contact with the gum 164, by the passage of the blank between pressing rolls 176 and 177, the latter of which has a cutaway portion 178, to prevent interference with the gum 172 on the seal flap. The shafts of said rolls have 110 intermeshing gears 179 and 180, the former 115 of which is driven through an idler 181 from the gear 152 of shaft 150.

The envelop is thus completed save for the turning down of the seal flap, which has already been partially creased by the action 120 of blade 157 and groove 159. The seal flap folding mechanism comprises stationary guides 182 and 183, in the form of transverse bars above and below the plane of advance of the envelop, and just in advance of the 125 pressure rolls 176 and 177. Beyond said bars 182 and 183 the folded bottom edge of the envelop encounters upwardly inclined deflecting members 184 which depend from a transverse rod 185. Said members 184, 130

which are preferably two in number and spaced apart, as shown in Fig. 1, have projecting stops 186 thereon with which the advancing bottom edge of the envelop makes contact, as shown in Fig. 12, before the rear or seal flap has passed out of the bight of pressure rolls 176 and 177. In assuming the position shown in Fig. 12, the envelop is acted upon by upper rod 183 which causes the bending of the seal flap along its creased line 162. In the further advance of said seal flap by the pressure rolls 176 and 177, this bending effect is increased until finally, upon the passage of the seal flap beyond said 10 rolls, the upward deflection of said seal flap is accomplished, around the lower rod 182 as a fulcrum. Simultaneously with this action, as shown in Fig. 13, a pair of swinging fingers 187, carried on shaft 188, descend 15 into contact with the folded bottom edge of the envelop, the ends of said fingers being notched, as at 189, to insure engagement with said edge. The descent of said fingers completes the folding of the seal flap, which 20 is thus kept out of contact with the back wall of the envelop, and simultaneously projects said completed envelop into the spaces of a suitable drying chain 190, or other envelop receiving instrumentality, driven by 25 gearing 191, 192 and 193 from gear 181.

The shaft 188 is driven by a gear 194 thereon, which is in turn driven, through gearing 195 and 196, from the gear 179 of roll 176. The fingers 187 operate to make 30 a revolution for each envelop arriving against the members 184, whereby the seal flap of each is folded, as above described. A modification of the seal flap folding devices is shown in Fig. 14, wherein the folding 35 fingers 197, instead of rotating, are carried on a rock shaft 198, which is oscillated by a link 199 connecting the same with a crank 200 on the gear 195, the operation being substantially the same as described in connection 40 with Figs. 12 and 13.

I claim,

1. In an envelop machine, the combination of blank cutting means, means for continuously advancing a blank, conical blank 50 rotating rolls, means for laterally and longitudinally alining said blank, said alining means being dependent for its operation on the leading wedged shaped flap of said blank, means for folding said blank, and means for ejecting said blank after folding.

2. In an envelop machine, the combination of blank cutting means, means for continuously advancing a blank, conical blank 60 rotating rolls, means for laterally and longitudinally alining said blank, said alining means being dependent for its operation on the leading wedged shaped flap of said blank, means for printing said blank, means for folding said blank, and means for ejecting 65 said blank after folding.

3. In an envelop machine, the combination of blank cutting means, means for continuously advancing a blank, conical blank rotating rolls, stationary means for laterally and longitudinally alining said blank, means 70 for gumming said blank, means for folding said blank, and means for ejecting said blank after folding.

4. In an envelop machine, the combination of blank cutting means, conical segmental 75 blank rotating rolls, stationary means for alining said blank, means for folding said blank, and means for ejecting said blank after folding.

5. In an envelop machine, the combination 80 of blank cutting means, conical blank rotating rolls, means for gumming said blank, means for laterally and longitudinally alining said blank, said alining means being dependent for its operation on the leading 85 wedged shaped flap of said blank, means for folding said blank, and means for ejecting said blank after folding.

6. In an envelop machine, the combination of blank cutting means, conical blank rotating rolls, means for gumming said blank, means for laterally and longitudinally alining said blank, said alining means being dependent for its operation on the leading 90 wedged shaped flap of said blank, means for printing said blank, means for folding said blank, and means for ejecting said blank after folding.

7. In an envelop machine, the combination 100 of blank cutting means, means for rotating a blank in transit in the plane of its advance, means for gumming said blank, a revoluble blade for creasing the bottom flap of said blank in a line at right angles to the line of advance of the blank, parallel stationary guides for folding the bottom flap, and means for advancing the blank between 105 said guides.

8. In an envelop machine, the combination 110 of blank cutting means, means for rotating a blank in transit in the plane of its advance, means for gumming said blank, means for creasing the bottom flap of said blank in a line at right angles to the line of advance of the blank, a pair of stationary guides for 115 folding the bottom flap, means for advancing the flap between said guides, and means for applying pressure to the bottom flap after being so folded.

9. In an envelop machine, the combination 120 of blank cutting means, means for rotating a blank in transit in the plane of its advance, means for gumming the blank, means for creasing the bottom flap of said blank in a line at right angles to the line of advance 125 of the blank, a pair of parallel spaced guides for folding the bottom flap, and means for applying pressure to the bottom flap after being so folded.

10. In an envelop machine, the combina- 136

- tion of a pair of continuously rotating rolls for forwarding a blank in a horizontal plane, one of said rolls having gumming surfaces for applying gum to the envelop blank as it passes between said rolls, to gum the side flaps and the seal flap, means carried by said rolls for creasing the back and seal flaps, and means for applying adhesive material to the gumming surfaces of one of said rolls.
10. 11. The combination of means for laterally and longitudinally alining a blank, said alining means being dependent for its operation on the leading wedge shaped flap of said blank, means for folding the side flaps of said blank, a revolute blade for creasing the bottom flap of said blank, stationary rods, pressure rolls coöoperating with said rods for folding said bottom flap, and means for ejecting said blank after folding.
15. 12. The combination of means for alining a blank, means for folding the side flaps of said blank, means for gumming said blank, a revolute blade for creasing the bottom flap of said blank, stationary rods, pressure rolls coöoperating with said rods for folding said bottom flap, and means for ejecting said blank after folding.
20. 13. In an envelop machine, the combination of blank cutting means, means for rotating a blank in transit in the plane of its advance, a revolute blade for creasing the seal flap of said blank, stationary guides, and a swinging member for coöperation with said guides for folding said seal flap and for ejecting said blank.
25. 14. In an envelop machine, the combination of blank cutting means, means for rotating a blank in transit in the plane of its advance, means for gumming said blank, a revolute blade for creasing the seal flap of said blank, stationary guides, and a swinging member for coöperation with said guides for folding said seal flap and for ejecting said blank.
30. 15. In an envelop machine, the combination of blank cutting means, means for rotating a blank in transit in the plane of its advance, means for gumming said blank, a revolute blade for creasing the seal flap of said blank, stationary guides, and a swinging member for coöperation with said guides for folding said seal flap and for ejecting said blank.
35. 16. In an envelop machine, the combination of blank cutting means, conical blank rotating rolls, means for alining said blank, side flap folding means, a revolute blade for creasing the seal flap of said blank, stationary guides, and a swinging member for coöperation with said guides for folding said seal flap and for ejecting said blank.
40. 17. In an envelop machine, the combination of blank cutting means, conical blank rotating rolls, means for folding the seal flap of said blank, comprising a revolute blade for creasing said seal flap, stationary guides and a swinging member for coöperation with said guides for folding said seal flap and for ejecting said blank after folding.
45. 18. In an envelop machine, the combination of blank cutting means, conical blank rotating rolls, means for alining said blank, side flap folding means, means for printing said blank, means for gumming said blank, a revolute blade for creasing the seal flap of said blank, stationary guides, and a swinging member for coöperation with said guides for folding said seal flap and for ejecting said blank.
50. 19. In an envelop machine, the combination of blank cutting means, conical segmental blank rotating rolls, means for gumming the blank, a revolute blade for creasing the seal flap of said blank, stationary guides, and a swinging member for coöperation with said guides for folding said seal flap and for ejecting said blank.
55. 20. In an envelop machine, the combination of blank cutting means, means for rotating a blank in transit in the plane of its advance, a revolute blade for creasing the bottom flap of said blank, stationary guides and segmental pressure rolls for folding said flap, means for folding the seal flap of said blank, and means for ejecting said blank after folding.
60. 21. In an envelop machine, the combination of blank cutting means, conical segmental blank rotating rolls, means for folding the side flaps of said blank, a revolute blade for creasing the bottom flap of said blank, stationary guides and segmental pressure rolls for folding said bottom flap, means for folding the seal flap of said blank, comprising a revolute blade for creasing said seal flap, stationary guides and a swinging member for coöperation with said guides for folding said seal flap and for ejecting said blank after folding.
65. 22. In an envelop machine, the combination of blank cutting means, conical segmental blank rotating rolls, reciprocating means for folding the side flaps of said blank, means for printing said blank, a revolute blade for creasing the bottom flap of said blank, stationary guides and segmental pressure rolls for folding said bottom flap, means for folding the seal flap of said blank, comprising a revolute blade for creasing said seal flap, stationary guides and a swinging member for coöperation with said guides for folding said seal flap and for ejecting said blank after folding.
70. 23. The combination of means for laterally and longitudinally alining a blank, said alining means being dependent for its operation on the leading wedge shaped flap of said blank, reciprocating means for folding the side flaps of said blank, means for printing said blank, means for gumming said

- blank, a revoluble blade for creasing the bottom flap of said blank, stationary guides and segmental pressure rolls for folding said bottom flap, means for folding the seal flap 5 of said blank, comprising a revoluble blade for creasing said seal flap, stationary guides and a swinging member for coöperation with said guides for folding said seal flap and for ejecting said blank after folding.
24. In an envelop machine, the combination of blank cutting means, conical segmental blank rotating rolls, means for laterally and longitudinally alining said blank, said alining means being dependent for its operation on the leading wedged shaped flap of said blank, reciprocating means for folding the side flaps of said blank, means for printing said blank, means for gumming said blank, a revoluble blade for creasing the bottom flap of said blank, stationary guides and segmental pressure rolls for folding said bottom flap, means for folding the seal flap of said blank, comprising a revoluble blade for creasing said seal flap, stationary guides and a swinging member for coöperation with said guides for folding said seal flap and for ejecting said blank after folding.
25. In an envelop machine, the combination of blank cutting means, means for rotating a blank in the plane of its advance, a revoluble blade for creasing the bottom flap of said blank, stationary guides and segmental pressure rolls for folding said bottom flap, means for folding the seal flap of said blank, comprising a revoluble blade for creasing said seal flap, stationary guides and a swinging member for coöperation with said guides for folding said seal flap and for ejecting said blank after folding.
26. In an envelop machine, the combination of blank cutting means, conical blank rotating rolls, means for alining said blank, a revoluble creasing blade, stationary guides and segmental pressure rolls for folding said bottom flap, means for gumming said blank, means for folding the seal flap of said blank, comprising a revoluble creasing blade, stationary guides and a swinging member for coöperation with said guides for folding said seal flap and for ejecting said blank after folding.
27. In an envelop machine, means for continuously advancing a web of paper, means for severing a blank from the web, means for advancing the severed blank, means for applying gum to one of the side flaps, means for folding the side flaps of the blanks, means for withdrawing the blank from the side flap folding mechanism, means for printing the blank, and means for advancing the blank from the printing mechanism.
28. In an envelop machine, the combination of means for advancing a web of paper, means for severing a blank from the web, 65 means for advancing the blank, means for rotating the blank in transit and in the plane of its advance, means for gumming one of the side flaps before the side flaps are folded, means for folding the side flaps, 70 means for gumming the folded side flaps, means for creasing the bottom flap, and means for folding the bottom flap.
29. In an envelop machine, the combination of blank cutting means, conical blank 75 rotating rolls, means for alining said blank, means for folding the side flaps of said blank, a revoluble cylindrical segment carrying a blade for creasing the bottom flap of said blank, a ledge for applying a strip of 80 gum to the uppermost faces of said side flaps, a blade for creasing the seal flap and a ledge for applying a strip of gum to said seal flap, means for folding said bottom flap, comprising stationary guides and pressure rolls, and means comprising stationary guides and a swinging member for coöperation with said guides for folding the seal flap and ejecting the folded blank in one 85 operation.
30. In an envelop machine, the combination of means for continuously advancing a web of paper, means for forming said web into blanks during the continued advancement of said web, conical blank rotating 90 rolls, means for laterally and longitudinally alining said blank, said alining means being dependent for its operation on the leading wedged shaped flap of said blank, means for folding the bottom flap, means for folding 95 the seal flap, and means for ejecting said blank after folding.
31. In an envelop machine, the combination of blank forming cutters, a revoluble cylinder for carrying said cutters, a revoluble cylinder co-acting with said cutter carrying cylinder, conical blank rotating rolls, means for laterally and longitudinally alining said blank, said alining means being dependent for its operation on the leading wedged shaped flap of said blank, means for printing said blank, reciprocating means for folding the side flaps of said blank, a revoluble blade for creasing the bottom flap of said blank, stationary guides and pressure rolls for folding said bottom flap, means for folding the seal flap of said blank, comprising a revoluble blade for creasing said seal flap, stationary guides and a swinging member for coöperation with said guides for 100 folding said seal flap and for ejecting said blank after folding.
32. In an envelop machine, the combination of blank forming cutters, revoluble cylinders for carrying said cutters, revoluble cylinders co-acting with said cutter carrying cylinders, conical blank rotating rolls, means for alining said blank, means for printing 105
- 110
- 115
- 120
- 125

said blank, means for folding the side flaps of said blank, means for gumming said blank, a revoluble cylinder carrying a blade for creasing the bottom flap and a blade for creasing the seal flap, stationary guides and pressure rolls for folding said bottom flap, stationary guides and a swinging member for coöperation with said guides for folding

said seal flap and for ejecting said blank after folding.

10

Dated this 8th day of October 1917.

ABRAHAM NOVICK.
